pany, a corporation of Delaware

Application May 29, 1948, Serial No. 30,102

3 Claims. (CL 255—14)

1

The present invention relates to a novel procedure for obtaining core samples of unconsolidated material in an oil well. In particular the invention relates to a method and apparatus for injecting a thermoplastic material into a porous formation to be sampled thereafter. The thermoplastic material is allowed to harden, and by conventional coring procedures a core is recovered. By suitably extracting the thermoplastic material the core may then be returned to its original state as it exists in the earth. In accordance with the preferred adaptation of the present invention a chemically inert naturally occurring petroleum wax is employed. This material will consolidate the formation to be removed and tested and is itself readily removable when the consolidated sample is brought to the surface.

In the expensive procedure of drilling into the earth in an attempt to find oil deposits, it is important to obtain all possible information as to the nature of the earth through which drilling operations are conducted. An important procedure generally conducted in this connection is to obtain core samples of the strata penetrated by the drilling tools. Thus in conventional operations when a point has been reached in the bore hole at which it is desired to obtain a core sample, the drill bit is removed from the drill stem and a core barrel substituted. The core barrel will cut a core of the particular stratum existing at the bottom of the drilling hole, and will permit bringing to the surface of the earth a sample of this core. However, when the stratum at the bottom of the drill hole is not a consolidated stratum, but is a loose and porous stratum, the conventional procedures heretofore known to the art are not suitable for recovering an unaltered sample of the core. Thus, if the stratum to be sampled consists of a loose sand formation, such as a type of sand in which oil may be found, due to the loose unconsolidated material of the sand, penetration by a coring tool disrupts the structure of the sand and defeats all attempts to obtain an unaltered core sample. It is, therefore, the principal object of this invention to provide apparatus and procedure for suitably obtaining an unaltered sample of unconsolidated material encountered in drilling operations.

In accordance with the present invention, therefore, when conventional drilling operations have proceeded until a porous or unconsolidated stratum is encountered, the drilling tools are removed from the bore hole and an apparatus lowered to the bottom of the hole, suitable for injecting a thermoplastic material into the un-

2

consolidated formation. The thermoplastic material is lowered to the bottom of the well so that it may be injected at a temperature of about 15° to 60° F., above the temperature existing at the bottom of the bore hole. The thermoplastic material is so chosen that it will harden at the bottom hole temperature. After the material has suitably been injected into the unconsolidated stratum, and time has been allowed for it to harden in the stratum, the material will bind the particles of the porous formation sufficiently to permit a conventional coring tool to cut and remove an unaltered sample of the formation. When this sample has been brought to the surface of the earth, it may be removed from the coring tool and may be suitably imbedded in a hard plastic or metallic cylinder so as to support it during heating or solvent operations adapted to remove the thermoplastic material. The result will be a true and unaltered sample of the unconsolidated stratum, just as it existed at the bottom of the bore hole. It is possible to examine this sample for porosity, permeability, connate water, and production characteristics as well as other properties. It is apparent that this information will be extremely valuable in assessing the oil producing possibilities of the particular stratum sampled.

It is contemplated that any thermoplastic material may be injected into the unconsolidated stratum. However, as pointed out heretofore the preferred adaptation of the present invention is to utilize a hydrocarbon or ester wax, preferably a naturally occurring petroleum oil wax. A basic requirement of the material to be injected is that it be liquid at a temperature somewhat above the bottom hole temperature, and that it solidify at the temperature existing at the bottom of the well. It is apparent that the choice of the material will be dependent on the particular temperature existing at the bottom of the bore hole, which factor in turn is in large part dependent on the depth of the well. It is presently thought that although other suitable thermoplastic materials may be generally employed, the preferred material of the present invention comprises petroleum wax.

Other waxes such as natural or synthetic ester waxes may also be utilized in practicing this invention but normally no advantage will be gained thereby, and a petroleum wax of suitable melting point will be found to be entirely satisfactory from the standpoint of both cost and availability. Of course, where bottom hole temperatures are higher than the melting points of available pe-

trolemum waxes, use must be made of higher melting hydrocarbon or ester waxes such as carnauba wax, ozocerite, montan wax, or of other materials such as asphalt, rosin, etc. A number of synthetic waxes are commercially available with melting points in the range of 200-300° F. and at least one is reported having a melting point in the vicinity of 400° F.

By employing waxes, particularly naturally occurring petroleum waxes, in accordance with the preferred embodiment of the present invention desirab¹ results are obtained. As pointed out heretofore the temperature in the bottom of any particular bore hole will vary generally with the depth. Thus the particular wax fraction which is most suitable for any particular depth may be readily selected. Furthermore by employing these waxes as consolidating mediums it is easy to remove the same readily without damage to the core at the surface, thus preserving the core sample in its natural condition. This represents a distinct improvement and advancement over other consolidating mediums since in many cases removal of the mediums from the core at the surface results in damage to the sand grains.

At the present time waxes are commercially available having any desired melting point within a fairly broad range making it possible to readily choose and obtain a suitable wax for a particular bottom hole temperature. For instance the following data illustrate the variance of bottom hole temperature with depth and the melting point of the wax to be used as well as the desirable temperature for injecting the wax into the bottom hole formation.

Approximate average temperatures in bore hole varying with depth

vs.

Preferred melting wax to be employed

Depth	Bore Hole Approximate Temp., ° F. ¹	Wax Melting Point, ° F.	Injection Temperature, ° F.
1,000	95	110-120	130-140
2,000	115	130-140	150-160
3,000	135	150-160	170-180
4,000	155	170-180	190-200
5,000	175	190-200	210-220
6,000	195	210-220	230-240
7,000	215	230-240	250-260
8,000	235	250-260	270-280
9,000	255	270-280	290-300
10,000	275	290-300	310-320
11,000	295	310-320	330-340
12,000	315	330-340	350-360

¹ It is to be understood that bore hole temperatures vary widely with depth depending upon the particular area or the earth's surface. The above are merely illustrative. When the temperatures vary with the area the melting points of the waxes utilized should be adjusted accordingly.

Although the melting point of the particular wax fraction used may vary appreciably it is evident that the melting point must be higher than the temperature which exists in the bottom of the bore hole. In general it is preferred that the particular wax fraction used have a melting point in the range from about 15° to 25° F. higher than the temperature existing in the bottom of the bore hole. Similarly it is preferred that the particular wax fraction be injected into the bore hole at a temperature in the range of about 20° F. to 50° F. above the melting point of the particular fraction employed.

The apparatus employed to inject the wax into the unconsolidated stratum may be of great simplicity, although it is preferred to employ a more

complicated apparatus. Thus all that is actually required to inject the wax is a suitable wax containing chamber, suspended at the bottom of a drill stem, having valves on either end of the chamber to control the influx and out-flow of liquid through the chamber. As the wax may be heated at the surface of the earth to a fairly high temperature before placing the wax in the chamber referred to, the chamber may be lowered to the bottom of the bore hole while the wax is still in a liquid stage.

In the event that the distance through which the chamber must be lowered is so great that considerable time will be spent in the descent, solidification of the wax may be prevented by providing the wax containing chamber with sufficient insulation for this purpose, or by fitting the chamber with suitable heating means, as for example electrically heated coils.

When the chamber has been suitably lowered to the bottom of the hole, by opening the valves of the chamber, drilling mud or other fluid may be pumped down the drill stem to force the wax out of the chamber and into the stratum at the bottom of the bore hole. When the wax has suitably been injected in this manner, it only remains to remove the chamber from the well and to use conventional coring equipment to recover a suitable sample of the formation.

As stated, however, it is preferred to use a somewhat more complicated apparatus for the wax injection. For example, it is preferred to heat the wax containing chamber to insure the liquefaction of the wax at the time it reaches the bottom of the bore hole. For this purpose it is convenient to employ an electrical heating coil in the wax containing chamber, suitably supplied with electricity through conductors leading to a source of current at the surface of the earth so that the wax may be maintained in a liquid state regardless of the time, or cooling effects encountered on lowering the wax containing chamber to the bottom of the bore hole. The heat requirements may be calculated sufficiently accurately so that a given size electrical coil may be used, or alternatively an excessively large heating coil may be employed together with a thermocouple placed in the wax to enable control of the heat input, and, thus, to permit control of the temperature of the wax. It is also preferred that the apparatus have means for sealing off the bottom of the bore hole to prevent any bypassing of the wax released from the chamber, and to insure suitable penetration of the wax to the porous stratum. The bore hole may be conveniently sealed off by employing an elastic packer which may be inflated to contact and thoroughly seal the lowermost part of the bore hole. Thereafter on applying pressure to force the wax from the wax chamber, the wax will be positively driven into the lower part of the bore hole without any possibility of bypassing the wax upwardly in the drilling hole. In this embodiment of the invention, it is preferred to employ an auxiliary air containing chamber which is opened simultaneously with the release of the wax so that displaced drilling mud and fluids trapped below the elastic packer may be pumped into the air filled chamber.

A further extremely simple form of apparatus that could be used consists merely of a section of tubing, filled with the melted wax, and closed at the bottom by a trip valve which would operate as described below. The section of tubing with the liquid wax inside temporarily prevent-

ed from escaping by the trip valve, would merely be dropped into the open drill hole. Upon striking bottom, the trip valve would be arranged so as to open, and pumping fluid into the hole thereafter as suggested hereinbefore would cause the melted wax to enter the unconsolidated formation. It will be understood that in practising this embodiment of the invention, the section of tubing would preferably be provided at the top with a hook or other means, well known to the art, to facilitate withdrawing it from the hole after the injection of wax was finished, in order that the operation of cutting a core consolidated by the solidified wax might next be carried out.

As stated, once the thermoplastic material, such as wax has been injected into the unconsolidated stratum, and has been allowed to harden, any conventional coring procedure may be employed to recover a suitable sample. As the coring procedures used are no part of the present invention, they will not be described in detail. It is to be understood, however, that the procedures used generally are suitable for cutting a cylindrical core of the stratum to be sampled, and of holding the core in the core receiving chamber so that the core may be brought to the surface of the earth. If desired, orienting devices may be employed with the core cutter so as to get information as to the exact orientation of the core in the earth. Knowing this information it is possible to tell exactly how the core obtained is positioned in the bore hole with respect to the directions of the compass, and with respect to the inclination of the core sampler.

When the core sample has been brought to the surface of the earth, any suitable procedure may be used for eliminating the thermoplastic material so as to restore the sample to its original condition, as it was in the bottom of the bore hole. However, it is preferred to remove the cylindrical core from the coring apparatus and to grind down the two faces of the core to provide flat, parallel faces. A porous plate is placed over each of these faces and the entire core is imbedded in a suitable supporting material, the exterior sides of the porous plates being, of course, left exposed. For example, the core may be imbedded in a hard plastic, such as phenol-formaldehyde, urea-formaldehyde or methylmethacrylate, or it may be imbedded in a low-temperature-melting alloy such as Woods metal. The only requirement for the material to be used is that it harden at a relatively low temperature and that it have sufficient strength to hold the core sample firmly. When this has been done it is possible to force a suitable solvent as for example benzene, toluene, or an alcohol, preferably butyl or amyl, through the perforated plates so as to remove the wax material originally used to consolidate the porous formation sample.

Certain other solvents may also be used for the above purpose, such as a naphtha fraction or a chlorinated hydrocarbon, for example, carbon tetrachloride or trichloroethylene. Selection of a suitable solvent is governed by its solvent power for wax, crude oil, and asphalt. In addition, the solvent used must not attack or react with the metal or plastic used to encase the core. It is of course to be understood that if a thermoplastic material other than wax is used, suitable solvents for removing that particular material will be selected.

It is also possible to remove the wax from the

core merely by application of sufficient heat to melt it, although the use of solvents is ordinarily more desirable. It is also often helpful to apply heat when employing solvents, so as to enhance the solvent action. After the wax has been removed from the core, it is apparent that the core will be in exactly the condition in which it existed at the bottom of the bore hole prior to sampling.

Preferred embodiments of the apparatus and procedure of this invention incorporating the features mentioned above are fully described in connection with the accompanying drawings in which Figure 1 represents the simplest form of apparatus suited for the purposes of this invention, in which Figure 2 represents a preferred form of apparatus incorporating an elastic packer and a mud receiving chamber, and in which Figure 3 represents an additional element which may be attached to the bottom portion of the form of apparatus represented by either Figure 1 or Figure 2.

Referring now to Figure 1, numeral 1 designates a bore hole drilled into the earth. It is to be understood that the bore hole is drilled until an unconsolidated formation 3 is encountered. At this time the method and apparatus of the present invention are employed for the purpose of obtaining an unaltered sample of the unconsolidated stratum. The drilling apparatus is removed from the bore hole and the apparatus illustrated in Figure 1 is threaded on to the drill stem 2. The apparatus comprises a case 3 which may be threaded on to the drill stem 2, or may be attached to the drill stem in any desired manner. An inlet port 4 to the chamber 3 is closed by a solenoid operated valve 5, while the outlet 6 at the lower end of the chamber is terminated by a similar solenoid valve 7. These valves are of conventional construction, being suitable for operation on activation by an electrical current supplied to the valves through conductors not illustrated in the drawing. It is to be understood that the chamber 3, made of any suitable material, has been filled with a thermoplastic material, preferably wax, before the chamber is lowered into the bore hole. As stated, this wax material is a wax which will solidify at the temperature existent at the bottom of the bore hole. This temperature will generally be known with sufficient accuracy by ascertaining the depth of the bore hole so as to permit choice of a suitable wax material. Alternatively, prior to the choice of the wax, a thermocouple or other temperature measuring means may be lowered to the bottom of bore hole 1 to accurately determine the temperature. In any case wax is introduced into chamber 3 prior to lowering the chamber into the bore hole. When chamber 3 has been lowered into the bottom of the bore hole, and sufficient weight has been put on the chamber to force the opening 6 somewhat into the porous formation, solenoid valves 5 and 7 are opened and a hydrostatic pressure is supplied to the drill stem in order to force the wax from chamber 3 into the porous formation 8. The hydrostatic pressure to force the material from chamber 3 may be readily supplied by filling the drill stem with drilling mud and then applying a pumping force to the drilling mud in the drill stem. It is to be understood that while the chamber is lowered and up to the time the thermoplastic material is forced into the chamber 3 it is necessary that the material be in liquid state. This may be readily accomplished by heating the wax material to a high temperature before placing it in the chamber 3. Alternatively, the material can be kept in a liquid state by supplying heat-

ing elements in the chamber 3, as will be described in connection with Figure 2.

Referring now to Figure 2, a preferred embodiment of the apparatus of this invention is illustrated. Again the apparatus is threaded on to, or suitably connected to the drill stem 2 to support the apparatus, and to permit it to be lowered into the bore hole 1. In the embodiment illustrated, an inner chamber 10 is provided with an annular spaced outer chamber 11 and an elastic packer 12, which is shown to be in the inflated position. The elastic packer 12 may be of conventional construction. The packer comprises a flexible membrane such as rubber, cloth or metallic fabric. The packer is thus of such a nature that it can be inflated or deflated so as to permit sealing the packer against the bore hole so as to effectively seal the hole. As illustrated, an inlet port 13 may be provided at the upper end of the apparatus, adjacent the drill stem. This opening provides a fluid passageway into the annular space between the elastic packer 12 and the outer part of chamber 10. The passageway 13 is provided with a solenoid operated valve 14 to control influx of fluid beneath the elastic packer. It is apparent that when drilling mud or other fluid is pumped down the drill stem 2 while valve 14 is open, the elastic packer will be inflated, thus forcing the packer against the walls of the bore hole, as illustrated. A passageway 15 is provided from the inner part of the elastic packer to the well, external of the drill stem 2. This passage is provided with a check valve 16. This check valve may consist of a spring operated valve so placed as to prevent flow of fluid from the bore hole external of the drill stem into the packer while permitting flow at a given pressure from the elastic packer into the bore hole. Thus if the check valve is spring operated, the spring may be so chosen that the valve 16 will open at a pressure sufficiently high to insure full inflation of the packer 12 without permitting rupture of the packer. Therefore, when drilling mud is pumped down the drill stem 2 through passageway 13 into the packer 12, check valve 16 will remain closed until the packer is fully inflated at which time the valve will open to permit bypassing of the fluid. The inner chamber 10 of the apparatus is the chamber to be filled with the wax material. The chamber 11 is a chamber to be filled with air prior to lowering the apparatus into the bore hole. Both of these chambers are supplied with valves to be operated as will be described. Chamber 10 may also be supplied with an electrical heating coil 17 which may operate through electrical conductors extending to the surface of the earth. For simplicity these conductors as well as the conductors leading to the solenoid valves have not been shown in the drawing. As in Figure 1 the wax filled chamber is sealed at the upper end by solenoid operated valve 18, closing inlet passageway 19, while the chamber is terminated at the lower end by passageway 20 provided with a solenoid valve 21. In using the apparatus of Figure 2, when the bore hole has been drilled until an unconsolidated formation 8 is encountered, the apparatus of Figure 2 is placed on the drill stem and chamber 10 is filled with wax or other thermal setting material as formerly described. The chamber 11 is filled with air, or if desired may be evacuated. The apparatus is then lowered into the bore hole, it being understood that packer 12 is in the deflated position while lowering.

Figure 3 illustrates a header element which can be attached to the base of the apparatus shown

in either Figure 1 or Figure 2. For convenience, this header element is shown connected to the base of the apparatus of Figure 2; header element 30 communicates with chamber 10 through passageway 20 controlled by valve 21. Attached to the header element are a plurality of tubular elements or prongs 31. These prongs or tubes may be of any suitable shape, that is, they may be of circular, square, triangular or similar cross section. For convenience, they are depicted as of circular cross section, that is, they are of generally cylindrical shape.

The header element may be of any suitable design. The header may contain attached thereto any number of hollow tubes or prongs. In general it is preferred that the number of these prongs range from 2 to 8, 5 being the preferred number. These prongs vary in length from 2 to 5 feet and have a diameter of $\frac{1}{2}$ to 1 inch, preferably about $\frac{3}{4}$ inch. The prongs may contain any suitable number of holes through which the wax or other suitable plastic material may be ejected therefrom. In general it is preferred that the diameter of these holes vary in the range of $\frac{1}{16}$ to $\frac{1}{8}$ inch. A preferred diameter comprises about $\frac{1}{16}$ inch. As the apparatus is lowered into the bore hole these prong elements 31 penetrate readily into formation 23. When the apparatus has been lowered until the prongs 31 are imbedded in the porous formation 23, the elastic packer 12 is inflated by pumping fluid, such as drilling mud through the drill stem, valve 14 having been previously opened. Pumping of fluid is continued until enough fluid has been provided to insure the opening of the bypass chamber 15, at which time valve 14 may be closed. It will be noted that inflation of the packer 12 effectively seals the lower part of the bore hole 1 so as to provide a sealed portion of the well immediately above the porous stratum 23. The thermo plastic material such as wax may then be extruded from the chamber 10 by opening valves 18 and 21 and by applying suitable pressure through the drill stem 2. The wax flows into header element 30 and into the prongs previously described. The wax then flows out into the surrounding formation through suitable openings 32 in the prong elements.

It is to be understood that the heating effect of coil 17 prior to extruding the thermo plastic material has been adjusted to insure that the material is in liquid state. As formerly indicated, this may readily be achieved by placing a thermocouple in chamber 10, not illustrated in the drawing, so as to indicate the temperature of the thermoplastic material in order that sufficient heat may be supplied through coil 17. When the thermoplastic material is forced from the chamber 10, the pressure applied will cause the material to be forced downwardly into the unconsolidated stratum 23, tending to displace fluid contained in the stratum.

It is apparent that sufficient pressure is applied to the drill stem 2 while extruding the wax to insure displacement of fluid approximately equal to the volume of chamber 10. By this means saturation of the stratum 23 with the wax in the vicinity of the apparatus described will be insured.

Having suitably filled a porous stratum with a thermoplastic material, as described, it is only necessary to remove the apparatus from the drill hole and to permit sufficient time for the thermoplastic material to reach the temperature existent at the bottom of the bore hole, which as has been stated is a temperature at which the material hardens. The result will, therefore, be

that the porous stratum 23 adjacent to the bottom of the bore hole will be saturated and supported by the hardened plastic material. By employing conventional coring tools, a core of the stratum may then be cut and the sample cut brought to the surface of the earth. It is preferred that when the sample is recovered, the ends of the sample be ground to provide smooth faces, to accommodate porous supporting plates such as fritted glass or wire screen. This assembly of core and the two end plates with the exception of the face of each end plate that is not in contact with the core, is then entirely imbedded in a suitable plastic, such as phenol-aldehyde or urea-aldehyde resin, polyvinyl acetate, polymethylmethacrylate, polystyrene, or the like, or in a low temperature melting alloy, such as Woods metal. When this material has suitably solidified, the core is subjected to solvent action through the perforated end plates to permit removal of the thermoplastic material originally used at the bottom of the bore hole. In the case where wax is used, for example, a suitable petroleum solvent or other solvent such as previously mentioned may be employed to dissolve the wax and return the core to the original condition it was in at the bottom of the bore hole. These steps having been carried out it will be apparent that the grains of the original unconsolidated stratum have been restored to exactly their original condition underground with respect to the rock composition and orientation of the grains. Consequently, the core sample may be examined for porosity, connate water, permeability and any other properties as desired.

As described, therefore, the present invention relates to a procedure and apparatus for obtaining an unaltered sample of unconsolidated strata encountered at the bottom of a bore hole. In accordance with the invention a suitable apparatus is employed to inject into the stratum a thermoplastic material which will harden to firmly hold the grains of the stratum. Thereafter a suitable core sample is cut from the stratum, the core is brought to the surface of the earth, and the thermoplastic material removed to leave the sample in exactly the same condition in which it existed at the bottom of the bore hole. The novelty of this invention will now be appreciated from the following claims.

What is claimed is:

1. In oil well operations the process of obtaining unaltered core samples comprising the steps of injecting a molten thermoplastic material into the stratum to be tested, hardening said material in the stratum whereby the particles of stratum

are bound, cutting a sample of the said stratum imbedded in the thermoplastic material, removing the said sample to the surface of the earth, and removing the thermoplastic material from said sample whereby a core is obtained wherein the sand grains are in a condition substantially the same as existed in said stratum, said thermoplastic material being characterized by having a melting point in the range of from 15° F. to 25° F. above the temperature existing in the bore hole at the point the sample is taken, said thermoplastic material being injected into said stratum at a temperature in the range of from about 20° F. to about 40° F. above the temperature at which said thermoplastic material melts.

2. A process as defined by claim 1 wherein the thermoplastic material comprises a wax.

3. In oil well operations the process of obtaining unaltered core samples comprising the steps of injecting a thermoplastic material into the stratum to be tested, hardening said material in the stratum whereby the particles of stratum are bound, cutting a sample of the said stratum embedded in the thermoplastic material, removing the said sample to the surface of the earth, smoothing two opposite faces of said sample, applying porous supporting plates to said faces, embedding the resulting assembly, with the exception of the outer faces of said plates, in a hardenable medium, hardening said medium and removing said thermoplastic material from said sample through at least one of said plates, whereby a sample is obtained wherein the sand grains are in a condition substantially the same as existed in said stratum.
